UNITED STATES PATENT OFFICE

2,521,296

BINDER

Edward C. Kinney, Chicago, Ill.

Application April 19, 1949, Serial No. 88,253

2 Claims. (Cl. 24—256)

1

This invention relates to a removable binder for holding loose sheets.

Among the objects of my invention is to provide a binder to be quickly and easily applied to loose sheets to hold them together, and which may be as quickly and easily released therefrom; to supply a holding means from which lower sheets may be pulled without disturbing the other sheets; to create a binder formed of cardboard and operated by rubber bands; to present a holder which will firmly hold sheets inserted therein and which does not change or otherwise affect the sheets.

My invention also contemplates such other objects, advantages and capabilities as will later more fully appear and which are inherently possessed by my invention.

While I have shown in the accompanying drawings a preferred embodiment of my invention, yet it is understood that the same is susceptible of modification and change without departing from the spirit of my invention.

Referring to the drawings, Fig. 1 is a top plan view of a blank and showing in part the addition of the fillers; Fig. 2 is an edge view of the same; Fig. 3 is an edge view showing the end portion folded over to provide with the filler the reinforced portions and Fig. 4 is a face view of the same; Fig. 5 is a face view of my binder showing the notches; Fig. 6 is an enlarged view of the binder ready for the addition of the resilient loops; Fig. 7 is a side elevational view of my device with the pad in place; Fig. 8 is a detailed view on line 8—8 of Fig. 7 and Fig. 9 is an end view of my binder.

The embodiment selected to illustrate my invention comprises a blank 10 preferably formed of cardboard with a glazed outer surface. My blank 10 is rectangular in shape with an upper edge 11 and a lower edge 12. A horizontal score 13 extends across blank 10 at a point downwardly from upper edge 11 forming upper end portion 14 and a corresponding horizontal score 15 extends across blank 10 at a point upwardly an equal distance from lower edge 12 forming lower end portion 16.

Downwardly spaced from score 13 an equal distance is horizontal score 17, forming adjacent portion 18, and correspondingly upwardly spaced from score 15 is horizontal score 19 forming adjacent portion 20. A filler 21 coextensive in size with adjacent portion 18 and preferably of cardboard is attached by a suitable adhesive to adjacent portion 18. A filler 22, coextensive in size with adjacent portion 20 and preferably of card-

board is attached by a suitable adhesive to adjacent portion 20.

Upper end portion 14 is then bent inwardly on score 13 and its inner surface attached by a suitable adhesive to the outer surface of filler 21 to form upper reinforced portion 23. Lower end portion 16 is also bent inwardly on score 15 and its inner surface attached by a suitable adhesive to the outer surface of filler 22, to form lower reinforced portion 24.

Downwardly spaced from score 17 an equal distance is horizontal score 25 forming upper intermediate portion 26 and correspondingly upwardly spaced from score 19 is horizontal score 27 forming lower intermediate portion 28. Between horizontal scores 25 and 27 is smaller central portion 29.

Upper and lower reinforced portions 23 and 24 are respectively bent inwardly on scores 17 and 19, and upper and lower intermediate portions 26 and 28 are respectively bent inwardly on scores 25 and 27.

Extending horizontally inwardly from each of the outer edges of upper and lower reinforced portions 23 and 24 are vertically spaced slots 30 and 31.

A resilient loop member 32, preferably a rubber band, is positioned to extend between opposite slots 30 of reinforced portions 23 and 24, and another resilient loop member 33, preferably a rubber band, is positioned to extend between opposite slots 31 of reinforced portions 23 and 24.

The smooth surfaces of reinforced portions 23 and 24 are adapted to receive between them inserted upper ends of a plurality of sheets. The bands 32 and 33 are adapted to stretch to permit the reinforced portions to be moved away from each other for the insertion of the sheets and then to contract to move the reinforced portions together again for holding the sheets in position.

Having thus described my invention, I claim:

1. A readily attachable and releasable binder for loose sheets comprising a pair of opposite reinforced end portions, a pair of spaced intermediate portions adjacent said end portions, and a central portion between said intermediate portions, scores separating said intermediate portions from said end portions and from said central portion, the outer edges of each of said end portions having a pair of spaced slots, said end portions bent inwardly on the scores between them and said intermediate portions, said intermediate portions bent inwardly on the scores between them and said central portion, so that said

end portions are opposite each other, and a pair of rubber bands extending around said end portions and positioned within said slots and contacting the outer surfaces of said end portions to move said opposite end portions into contact, said intermediate portions covering said rubber bands, said bands adapted to be stretched to permit said end portions to part to receive the ends of a plurality of loose sheets therebetween and to contract to move said end portions together to hold the inserted sheets.

2. A loose leaf binder comprising a central portion, a pair of opposite spaced integral intermediate portions bent inwardly from said central portion, a pair of opposite spaced integral end portions bent inwardly from the inner ends of said intermediate portions, and having cut outs on their outer edges, a resilient loop member extending around the outer surfaces of said end portions and positioned within said cut outs to move said end portions into contact, said intermediate portions covering said loop member, said

loop member adapted to be stretched to permit said end portions to be parted to receive the ends of a plurality of loose sheets therebetween, and to contract to move said end portions together to hold the inserted sheets.

EDWARD C. KINNEY.
